ABSTRACT: A precision variable high resistor for high-frequency use comprises a complex series condenser composed of three spaced, parallel plates. The intermediate plate is mechanically movable relative to the pair of outer plates in parallel relation thereto. The three plates comprise discs of dielectric material having thin metal electrodes attached to their facing surfaces; and the electrodes attached to their facing surfaces; and the electrode which is attached to one of said outer plates, and which faces said intermediate plate, is grounded. A fixed resistance is connected between said grounded electrode and the facing electrode on said intermediate plate.

PRECISION VARIABLE RESISTOR FOR HIGH-FREQUENCY USE

BACKGROUND OF THE INVENTION

Recently, in the measurement of a dielectric loss angle in a high frequency region, it has become necessary to measure very small dielectric loss, and the measuring frequency is becoming wider ranging from what is called wireless frequency to very high-frequency. A standard variable resistor of a high resistance value which is highly reliable throughout the wide frequency range is needed for the accurate measurement of a very small loss angle.

Recently synthetic insulating materials of excellent properties have been developed one after another and have been put into practical use. However instruments capable of accurately measuring ϵ and $\tan \delta$ of an insulator having a Q value 10^4 to 10^5 over the frequency range between 100 kHz. and 1,000 mHz. have not been developed.

SUMMARY OF THE INVENTION

An object of the present invention is to provide a standard variable resistor of a high resistance value for high frequency use which is highly reliable and has a high precision over a wide frequency range in order to meet the above-mentioned requirement.

The present invention brings such an advantage that a standard variable resistor of a high resistance value which has a high precision, a wide frequency range and a wide range of variable resistance value can be provided in a relatively simple construction. This desirable result is accomplished by use of a novel complex series condenser comprising three spaced, parallel plates wherein the intermediate plate is mechanically movable parallel to the outer plates. The plates comprise discs of dielectric materials having thin metal electrodes attached to their facing surfaces; and the electrode which is attached to one of said outer plates, and which faces said intermediate plate, is grounded. A fixed resistance is connected between said grounded electrode and the facing electrode on said intermediate plate. Measurements circuits are provided incorporating the described structure.

BRIEF DESCRIPTION OF THE DRAWINGS

FIGS. 1A, 1B and 1C respectively illustrate a combination of parallel plate capacitors and a resistor, and represent the principle of the standard variable resistor of a high resistance value for high frequency use according to the present invention.

FIGS. 2A and 2B illustrate the equivalent circuits of the combination shown in FIG. 1B.

FIGS. 3A and 3B illustrate the equivalent circuits of the combination shown in FIG. 1C.

FIG. 4 illustrates a first embodiment of the present invention operative to measure an unknown resistor R_x using the standard variable resistor of a high resistance value for high-frequency use.

FIG. 5A illustrates a second embodiment of the present invention in which the variable resistor of a high resistance value for high-frequency use according to the present invention is connected to a balanced tuning circuit for measuring purposes.

FIG. 5B illustrates the equivalent circuit of the variable resistor shown in FIG. 5A.

FIGS. 6A and 6B respectively illustrate a third embodiment of the present invention in which a variable resistor for high-frequency use is connected to a tuning circuit having a grounded common line, and the equivalent circuit thereof.

DESCRIPTION OF THE PREFERRED EMBODIMENT

The present invention will hereinafter be described in conjunction with the drawings. In FIG. 1A, circular parallel plates, or disc 1 and 2, which respectively have the same area A , comprise dielectric members of a dielectric constant ϵ_s having respective thicknesses t_1 and t_2 . Discs 1 and 2 are disposed in spaced parallel relation to one another, and are

parallel to a dielectric plate E, to provide gaps t_1 and t_2 on both sides of the disc 2. Very thin metal films or foils acting as electrodes are attached to the lower face of disc 1, to both faces of disc 2, and to the upper face of plate E; and a metal terminal T_1 is disposed adjacent the upper face of disc 1. Elements 1 and 2 accordingly constitute first and second parallel plate capacitors respectively. A grounded terminal T_2 is disposed adjacent the lower face of plate E. A fluid dielectric substance (air or liquid) having a dielectric constant ϵ_1 fills the gaps t_1 and t_2 . For purposes of understanding the subsequent description, it is convenient to designate $t_0 = t_1 + t_2$, and to designate $t_s = t_1 t_2$. In accordance with the present invention, and adopting these designations, $t_s > t_0$. For example, if $t_0 = 1$ mm., then $t_s = 10 \sim 20$ mm. The intermediate disc capacitor 2 located between the disc capacitor 1 and the dielectric plate E is made movable, through a small displacement while being maintained in parallel relation to the disc capacitor 1 and to the plate E, by means of a mechanism such as a micrometer. Even though the intermediate disc capacitor can be moved, t_0 remains constant.

The plate E is constructed as follows. A disc insulator of appropriate thickness is disposed between the aforementioned thin metal electrodes which are attached thereto. The lower one of these electrodes, attached to disc 2, has a thickness between 0.5 mm. and 1 mm. This lower electrode on disc 2 is connected, through a fixed resistor R_s , to the upper electrode on plate E (see Figs. 1B and 1C); and said upper electrode on plate E is in turn grounded by being connected to the aforementioned terminal T_2 .

The capacitances which are constituted by the gaps t_1 and t_2 and the respective metal electrodes bounding said gaps, are designated C_1 and C_2 respectively. C_2 is equal to $\epsilon_0 \epsilon_s A / t_2$, where ϵ_0 is the permittivity of free space. The capacitor group shown in FIG. 1B is represented by the equivalent circuit shown in FIG. 2A, and the following equation holds.

$$\frac{1}{Cr} = \frac{t_s}{\epsilon_0 \epsilon_s A} + \frac{t_1}{\epsilon_0 \epsilon_s A} = \frac{\epsilon_1 t_s + \epsilon_s t_1}{\epsilon_0 \epsilon_1 \epsilon_s A} \quad (1)$$

where $t_s = t_1 + t_2$. An angular frequency ω equals $2\pi f$, where f is the frequency of the power source used. In FIG. 2A, if the expression $\omega C_2 R_s \geq 10 \dots (2)$

is satisfied, the equivalent circuit of FIG. 2A may be transformed into that of FIG. 2B. And the following expressions hold in FIG. 2B.

$$\frac{1}{Cr} = \frac{t_s}{\epsilon_0 \epsilon_s A} + \frac{t_1}{\epsilon_0 \epsilon_s A} + \frac{t_2}{\epsilon_0 \epsilon_1 A} = \frac{t_s}{\epsilon_0 \epsilon_s A} + \frac{t_0}{\epsilon_0 \epsilon_1 A} = \text{constant} \quad (2)$$

$$R_{po} = \left(1 + \frac{C_2}{Cr} \right)^2 R_s = \left(1 + \frac{\epsilon_1 t_s + \epsilon_s t_1}{\epsilon_s t_2} \right)^2 R_s \quad (3)$$

Then, as shown in FIG. 1C, when the intermediate capacitor 2 makes a small displacement Δt toward the plate E, the equivalent circuit will become as shown in FIG. 3A, where

$$\frac{1}{Cr'} = \frac{\epsilon_1 t_s + \epsilon_s (t_1 + \Delta t)}{\epsilon_0 \epsilon_1 \epsilon_s A} \quad \text{and} \quad C_2' = \frac{\epsilon_0 \epsilon_1 A}{t_2 - \Delta t} \quad (4)$$

Further, the equivalent circuit of FIG. 3A may be transformed into that of FIG. 3B. In FIG. 3B, the expression

$$\frac{1}{Cr'} = \frac{1}{C_2'} + \frac{1}{\epsilon_0 \epsilon_1 \epsilon_s A} = \frac{t_s}{\epsilon_0 \epsilon_1 A} + \frac{t_1 + \Delta t}{\epsilon_0 \epsilon_s A} + \frac{t_2 - \Delta t}{\epsilon_0 \epsilon_s A} = \frac{t_s}{\epsilon_0 \epsilon_s A} + \frac{t_0}{\epsilon_0 \epsilon_1 A} \quad (5)$$

holds, so that the value of C_p in FIG. 2B is equal to that of C_p' in FIG. 3B. That is $C_p = C_p'$. Hence the capacitance C_p seen from terminals T_1 and T_2 is constant for any small displacement of the capacitor 2. On the other hand, R_{px} is represented by the following expression.

$$R_{px} = \left(1 + \frac{C_2'}{Cr'} \right)^2 R_s = \left\{ 1 + \frac{\epsilon_1 t_s + \epsilon_s (t_1 + \Delta t)}{\epsilon_s (t_2 - \Delta t)} \right\}^2 R_s \quad (6)$$

From the above results, a standard variable resistor of a high resistance value for high-frequency use is materialized to be adjustable by changing Δt .

In FIG. 4 which shows a first embodiment of the present invention wherein the standard variable resistor for high-frequency use above described is applied to a measuring circuit, at first, a test sample of a dielectric substance having a capacitance C_x and a resistance R_x is disconnected from the circuit by a switch S . In this state, the circuit is tuned by adjusting C_v . Let the tuned value of C_v be C_{v1} and the current flowing through the detector to be I_{go} . Next, after connecting the test sample of dielectric substance (C_x , R_x) in parallel with the terminals T_1 and T_2 by closing the switch S , the circuit is again tuned by the adjustment of C_v . Then the following expression holds: $C_x = C_{v1} - C_{v2}$

where C_{v2} is the tuned value of C_v when the sample is connected. In this case, the current flowing through the detector decreases from I_{go} due to the connection of R_x , but the said current can be made equal to I_{go} by adjusting the capacitor 2 of the variable resistor for high-frequency use to make a small displacement toward the plate E . Letting the displacement be Δt when the current flowing through the detector becomes I_{go} after the sample is connected to the circuit, from the relation of:

$$1/Rx + 1/Rpx = 1/Rpo,$$

the following expression holds.

$$Rx = Rpo \times \frac{1}{1 - Rpo/Rpx} \quad (5)$$

Substituting Rpo and Rpx in the expressions (3) and (4) for those in the equation (5), the following expression (6) is derived.

$$Rx = \left(1 + \frac{\epsilon_1 t_s}{\epsilon_0 t_0}\right)^2 \frac{t_0}{\Delta t} \times \frac{t_0}{2t_2} \times \frac{1}{1 - \Delta t/2t_2} R_s \quad (6)$$

In the expression (6), the values of ϵ_1 , ϵ_0 , t_0 , t_2 , and R_s are all known, so that the resistance value of the high value resistor R_x may be obtained from the measurement of Δt . Further, the Q -value of the test sample can also be obtained from the relation of $Q_x = \omega C_x R_x$.

In a special case that the capacitor 2 is firstly set as $t_2 = t_0$ and the fluid dielectric substance is air, hence ϵ_1 being equal to unity, the resistance value of the high value resistor R_x can be obtained from the following expression (7).

$$Rx = \left(1 + \frac{t_s}{\epsilon_0 t_0}\right)^2 \frac{t_0}{\Delta t} \times \frac{1}{1 - \frac{\Delta t}{t_0}} R_s \quad (7)$$

For example, if various parameters are chosen as follows, the diameter of the electrodes = 40 mm., $t_0 = 1$ mm., $t_1 = t_2 = 0.5$ mm., $t_s = 10$ mm., $R_s = 40$ K Ω , $\epsilon_0 = 5$ (for a glass plate), and $f = 2 \times 10^6$ Hz., the relation of $\omega C_2 R_s = 10$ holds, and if $\Delta t = 10 \mu$, $R_x = 36$ M Ω is obtained from the expression (7). If a liquid of $\epsilon_2 = 10$ is used as the fluid dielectric substance, $R_x = 1,764$ M Ω is obtained if $\Delta t = 10 \mu$, so that it is understood that the resistance value of the high-value resistor R_x can be measured over a very wide range of resistance value.

The second and the third modified embodiments of the present invention, wherein the standard variable resistor for high-frequency use according to the present invention is applied to measurement circuits, are described with reference to FIGS. 5A and 5B and FIGS. 6A and 6B respectively.

In FIG. 5A, there are shown parallel plate capacitors C_1 and C_2 having airgaps t_1 and t_2 respectively. An intermediate metal plate is grounded and the capacitance values of the capacitors C_1 and C_2 are represented by $C_1 = \epsilon_0 A/t_1$ and $C_2 = \epsilon_0 A/t_2$, respectively, where A is the area of each of the electrode plates of the capacitors C_1 and C_2 which are not grounded and ϵ_0 is the permittivity of free space. The intermediate grounded plate is made movable to make a small displacement up and down by means of a micrometer. Now, assuming $t_0 = t_1 + t_2$, when the intermediate grounded electrode is slightly displaced up or down by a displacement Δt , the capacitance values of the capacitors C_1 and C_2 change respectively, but a capacitance value C_{AB} across both end terminals A and B of the capacitors C_1 and C_2 is constant and never changes. That is,

$$\frac{1}{C_{AB}} = \frac{1}{C_1} + \frac{1}{C_2} = \frac{t_1 \pm \Delta t}{\epsilon_0 A} + \frac{t_2 \pm \Delta t}{\epsilon_0 A} = \frac{t_1 + t_2}{\epsilon_0 A} = \frac{t_0}{\epsilon_0 A} = \text{constant}$$

In FIG. 5A, when a standard fixed value resistor for high-frequency use R_s (for example, a carbon film resistor) is connected in parallel with the capacitor C_1 , an equivalent circuit may be represented with C_{AB} and R_s as shown in FIG. 5B, where the following expressions (8) and (9) of R_s and C_{AB} will hold.

$$R_s = \frac{1}{\omega^2 C_2^2 R_s^2} \left(\frac{C_2}{C_1} \right)^2 R_s + \left(1 + \frac{C_2}{C_1} \right)^2 R_s \quad (8)$$

$$C_{AB} = \frac{C_1 \{ 1 + \omega^2 C_2 (C_1 + C_2) R_s^2 \}}{1 + \omega^2 (C_1 + C_2)^2 R_s^2} \quad (9)$$

When the frequency f of a power source is designated by f the angular frequency ω is expressed by $\omega = 2\pi f$, and if the resistance value of the fixed resistor R_s is selected to satisfy the relation $1/\omega C_2 R_s < < 1$ or $\omega C_2 R_s > > 1$, the expressions (8) and (9) may be respectively represented as follows by considering the relation $\omega^2 C_2^2 R_s^2 > > 1$.

$$R_s = \left(1 + \frac{C_2}{C_1} \right)^2 R_s \quad (10)$$

$$C_{AB} = \frac{C_1 C_2}{C_1 + C_2} \quad (11)$$

by applying the relations $C_1 = \epsilon_0 A/t_1$ and $C_2 = \epsilon_0 A/t_2$ to the above expressions, the following expressions are derived.

$$R_s = (t_0/t_2)^2 R_s \quad (10)'$$

$$C_{AB} = \epsilon_0 A/t_0 = \text{constant} \quad (11)'$$

That is, the resistance value of R_x can be changed freely and continuously between R_s and infinity, while the capacitance value of C_{AB} remains unchanged.

In order to obtain a very high resistance value for a variable resistor R_p , which is an equivalent presentation of the variable resistor according to the present invention as seen from terminals T_1 and T_2 when the value of t_2 is not zero, capacitors C_0 which satisfy the relation $C_0 < < C_{AB}$ are inserted in series with the capacitor C_{AB} . Then, R_p is represented by the following expression (12).

$$R_p = \left(1 + \frac{2C_{AB}}{C_0} \right)^2 R_s = \frac{t_0^2}{t_2^2} \left(1 + \frac{2C_{AB}}{C_0} \right)^2 R_s \quad (12)$$

Thus, a standard variable resistor of a very high resistance value for high-frequency use is attained, whereby loss resistance of very low loss dielectric substances can be measured by a substitution method.

The test sample resistance R_x is represented by the following equation.

$$Rxs = \frac{t_0^2}{t_2^2 - t_{2x}^2} \left(1 + \frac{2C_{AB}}{C_0} \right)^2 R_s \quad (13)$$

wherein t_{20} is the gap of the capacitor C_2 at the beginning of measurement and t_{2x} is the gap thereof, and whereby a resistance value of the variable resistor according to the present invention can be substituted for Rxs of the text sample in the course of measurement.

The principle of the circuits in FIGS. 6A and 6B is completely the same as that of the circuits in FIGS. 5A and 5B. It is modified only in that the intermediate movable plate between the parallel plate capacitors is insulated from ground and the capacitor C_2 has its lower electrode plate grounded, because the tuning circuit for measurement is grounded at one common line thereof.

I claim:

1. A precision variable resistor for high-frequency use comprising three plates constituting a pair of outer plates and an intermediate plate mounted in spaced parallel relation to one another to define a pair of gaps therebetween each of said outer plates having a conductive electrode surface facing said intermediate plate, the opposing surfaces of said intermediate plate which face said outer plates respectively also being conductive, means for grounding the conductive electrode surface on one of said outer plates, a high frequency standard

fixed resistor bridging the gap between said intermediate plate and said one of said outer plates, said resistor being connected between said grounded electrode surface on said one of said outer plates and the conductive surface of said intermediate plate which faces said grounded electrode surface, and means for moving said intermediate plate relative to said pair of outer plates while maintaining the parallel relationship between said three plates thereby to vary the relative dimensions of said pair of gaps.

2. The structure of claim 1 wherein said one of said outer plates comprises a dielectric plate provided with metal electrodes on both surfaces thereof, said metal electrodes being electrically connected to one another and to ground to form a grounded electrode;

the other one of said outer plates comprising a parallel-plate 15 first capacitor including a dielectric member having a dielectric constant ϵ_s and a thickness t_{s1} ;

said intermediate plate comprising a thin parallel plate second capacitor including a dielectric member having a dielectric constant ϵ_s and a thickness t_{s2} and having thin 20 metal electrodes attached to both surfaces of said dielectric member.

said second capacitor being positioned in parallel with said first capacitor to define a gap t_1 therebetween, and said second capacitor being positioned in parallel to said dielectric plate to define a gap t_2 therebetween, both of 25 said gaps t_1 and t_2 being filled with a dielectric fluid having a dielectric constant ϵ_1 , whereby said three plates and said pair of gaps comprise a combination of serially arranged capacitors:

said high-frequency standard fixed resistor having a resistance R_s satisfying the condition: $2\pi f C_2 R_s \geq 10$ where f designates a power source frequency, and C_2 designates the capacitance of a capacitor constituted by the electrode of said second capacitor facing said gap t_2 , the 35

grounded electrode of said dielectric plate, and the gap t_2 filled with said dielectric fluid;

and means for connecting a test sample having an unknown resistance R_x in parallel with said combination of serially arranged capacitors, whereby the magnitude of R_x is measured by being substituted by a small displacement Δt of said second capacitor based on the following relation:

$$R_x = \left\{ 1 + \frac{\epsilon_1(t_{s1} + t_{s2})}{\epsilon_s(t_1 + t_2)} \right\}^2 \frac{t_1 + t_2}{\Delta t} \frac{t_1 + t_2}{2t_2} \frac{1}{1 - \Delta t/2t_2} R_s$$

3. A precision variable resistor resistor for high-frequency use comprising:

two serial parallel plate capacitors having capacitances C_1 and C_2 constituted by two fixed electrode plates and one movable electrode plate intervening between said two fixed electrode plates;

at least one capacitor having a small capacitance connected in series with said two serial parallel plate capacitors; a high-frequency standard fixed resistor having a resistance R_s connected in parallel with the one of said two serial parallel plate capacitors having a capacitance C_2 ; and means for varying said capacitance C_2 by shifting the position of said movable electrode plate relative to said two fixed electrode plates while satisfying the condition $2\pi f C_2 R_s > 1$

where f designates a power source frequency, whereby the combination of said two serial parallel plate capacitors and said high-frequency standard fixed resistor is reduced to a parallel circuit of an equivalent fixed capacitance C_{AB} and an equivalent variable resistance R_x so that only the resultant resistance R_x is freely and continuously varied while maintaining the resultant capacitance C_{AB} at a constant value.
